AND ONE-THIRD TO WALTER ROBERTS, BOTH OF RICHMOND HILL, NEW YORK.

WAGON-BODY.

1,394,798.

Specification of Letters Patent.

Patented Oct. 25, 1921.

Application filed August 14, 1919. Serial No. 317,497.

To all whom it may concern:

Be it known that I, JOHN SPEED, a citizen of the United States, and a resident of the city of New York, borough of the Bronx, in the county of Bronx and State of New York, have invented a new and Improved Wagon-Body, of which the following is a full, clear, and exact description.

This invention relates to wagon bodies and has particular reference to such bodies as are designed for use in connection with motor trucks for heavy load service and most reliable operation.

Among the objects of the invention is to provide a novel floor structure for a truck or wagon body having peculiarly strong, reliable and efficient stake supporting means.

Another object of the invention is to improve the construction of the wagon bodies with respect to the combined floor sills and stake supports.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a side elevation or edge view of a portion of a wagon body floor, one of the sills and a stake.

Fig. 2 is a plan view of the same portion of the floor shown in Fig. 1 and with the stake in section on the line 2—2 of Fig. 1.

Fig. 3 is a vertical sectional detail on the line 3—3 of Fig. 1.

Fig. 4 is a perspective view of one end of the sill and the stake socket, the flooring being omitted from this view; and

Fig. 5 is an end view of the sill.

Referring now more specifically to the drawings I show my invention as comprising a floor sill 10, it being understood that any number of these sills that may be desired will be employed and arranged usually transversely of the body. Each sill is composed in the preferred form of a metal I-beam 11 of a height corresponding to the full height of the sill. Fitted into each side of the I-beam is a block of wood 12 which

may be coextensive in length with the I-beam 55 or any length shorter as may be preferred. These blocks or filling strips are shaped or molded along their inner sides to conform to the surfaces of the I-beam or in other words each of the strips is provided with a 60 tongue 13 fitted into the side of the I-beam and directly against the vertical portion thereof, the top and bottom surfaces 14 and 15 of the strips lying flush with the top and bottom surfaces of the I-beam respectively. 65 Any suitable means may be provided to secure the two filling strips 12 and I-beam together making a permanent rigid sill structure and of perfectly rectangular form in cross section. To this end I employ any 70 suitable number of transverse bolts 16 passing through the three parts of the sill in addition to other means now to be described. The filling strips 12 being preferably of wood easily adapt themselves for the attachment 75 of the floor members 17 extending ordinarily longitudinally of the body, the attachment being effected either by nails or bolts, preferably the latter shown at 18.

One of the chief features of my improvement lies in the socket member shown as a whole at 19, the same comprising a U-shaped device having side portions or legs 20 and a front portion 21. These three portions may be described as each comprising a horizontal flange and a vertical flange, the three horizontal flanges lying flush with the top of the sill while the vertical flanges of the side legs 20 embrace the outer sides of the filling strips 12. An inner member or portion of the socket piece consists of a strut or bridge member 22 spanning the space between the legs 20 and lie spaced from and parallel to the front portion 21. The strut 22 is adapted to lie or abut snugly against 85 the end of the sill, and the space between the strut and the end member 21 constitutes a socket 23 for the stake 24. The socket member as a whole may be made by any suitable means such as by drop casting or forging 95 and providing for the rigidity thereof as well as permanency of form.

If desired the strut 22 may be omitted and the socket member in such event may easily be formed from a common angle bar 105 cut with a hack saw or the like at 21' and with the leg portions bent around parallel to each other and at right angles to the end

member 21, the saw cuts thus providing the right angular cuts out at the corners. If the socket member be made of an angle bar in this manner the end of the sill would have to be relied upon as the inner wall support for the stake. I prefer, however, that the socket member be made with the strut as illustrated thereby providing all solid walls for the stake and making a more rigid and reliable socket than if the end of the sill be relied upon. The horizontal flanges of the socket member are adapted for use in attachment of some of the floor pieces directly thereto and by means of bolts 18' passing through the floor pieces and holes 30 formed in the socket member. Bolts 31 passing through the vertical flange portions of the legs 20 serve to lock the socket member with the end of the sill and additionally bind the members of the sill together.

The stake is composed of a stick of wood or its equivalent having its lower end reinforced by means of a channel member 24' embracing the inner and edge walls of the stick. The stick is slotted at 25 at the lower end to straddle a locking screw 26 adapted to pass freely through a smooth hole 27 formed in the vertical flange portion of the end part of the socket member 21. Within the slot 25 is located a nut 28 with which the screw co-operates. The nut being held from rotation by the stake the turning of the screw therethrough will cause the point of the screw to impinge against the inner wall of the channel 24' with force proportional to the force applied to the rotation of the screw, the outer wall of the nut reacting squarely against the inner wall of the member 21. After the screw is tightened in this way it may be locked by means of a lock nut 29 on the outside of the member 21. The binding force of the screw reacting between the channel and the adjacent side wall

of the socket, makes a rigid, though separable, stake fastening. 45

I claim:

1. In a wagon body construction, a sill having a flat upper surface, a U-shaped stake socket member comprising side legs embracing the sides of the sill and an end piece integral with one another, the legs and end piece comprising horizontal flange members flush with the top surface of the sill; said end piece being spaced from the end of the sill forming a stake socket, and means passing through said legs to lock the socket member to the end of the sill. 50

2. In a wagon body construction, the combination of a sill of rectangular form in cross section and having a flat upper surface, a stake socket member having an end piece and side legs, the upper surfaces of which like flush with the upper surface of the sill and with the end piece spaced from the end of the sill forming a stake socket, floor pieces lying upon the sill and socket member, and means interlocking the socket member and the sill and means interlocking the floor pieces and the socket member. 60

3. In a wagon body construction, the combination of a stake, a sill comprising an I-beam and wooden filler members fitted to the sides thereof, a socket member comprising side leg portions embracing the outer sides of the filler members, locking members passing through the socket member, legs and sill to secure these parts together, the socket member including also an end piece spaced from the end of the sill and a strut member extending between the side legs and spaced from and parallel to said end member, the space forming a stake socket, and means acting through the end member of the socket piece to lock the stake 75 in the socket. 80

JOHN SPEED.
